UNITED STATES PATENT OFFICE.

EDWARD EVERETT SQUIRES, OF SEATTLE, WASHINGTON, ASSIGNOR OF ONE-HALF TO CHARLES E. HAYDON, OF SAME PLACE.

FRAMING-JOINT.

SPECIFICATION forming part of Letters Patent No. 643,552, dated February 13, 1900.

Application filed April 27, 1899. Serial No. 714,764. (No model.)

To all whom it may concern:

Be it known that I, EDWARD EVERETT SQUIRES, of Seattle, in the county of King and State of Washington, have invented a new and Improved Framing-Joint, of which the following is a full, clear, and exact description.

The invention relates to the manufacture of doors and like articles; and its object is 10 to provide a new and improved framing-joint more particularly designed for use in the manufacture of doors and the like, and which joint is simple and durable in construction and arranged to securely fasten the rails and 15 stiles together to give additional strength to the door and prevent the members of the joint from becoming loose from side pressure incident to the opening and closing of the door.

The invention consists of novel features 20 and parts and combinations of the same, as will be fully described hereinafter and then pointed out in the claims.

Reference is to be had to the accompanying drawings, forming a part of this specification, 25 in which similar characters of reference indicate corresponding parts in all the views:

Figure 1 is a cross-section of the rail. Fig. 2 is a like view of the stile. Fig. 3 is a reduced side elevation of a corner of a door provided with the improvement. Fig. 4 is a like view of a modified form of the improvement. Fig. 5 is a similar view of another modified form of the improvement, and Fig. 6 is a like view of still another modified form of the improvement.

The stile A, as shown in Figs. 2 and 3, is provided with a longitudinally-extending groove B, having its side walls B' curved and terminating in a bottom B² somewhat less in 40 width than the opening B³ at the top of the groove B. The stile A is formed with moldings or stickings C, having their inner faces forming part of the side walls B' of the groove, said moldings or stickings forming clamping-jaws, as hereinafter more fully described, the outer sides terminating on shoulders D.

The rail E is provided with a tenon F, having its sides corresponding to the side walls B' of the groove B, the bottom F' corresponding to the bottom B² of the groove, so that when the tenon is driven into the groove B

it completely fills the groove. The rail E is further provided with copings G on opposite sides of the tenon, the copings terminating in shoulders H, adapted to engage and be seated 55 on the shoulders D of the stile A. When the tenon F is driven into the groove B, the stickings or moldings C are somewhat spread apart to be finally pressed inward by the copings G at the time the rail is driven home, so that 60 the copings press the stickings or moldings in firm contact with the sides of the tenon F—that is, the stickings or moldings act as jaws to firmly clamp the tenon. The groove B extends throughout the length of the stile A, 65 and the portion between the two rails is filled by the edge of the panel I, as will be readily understood by reference to Fig. 4.

The side walls B' of the groove B may terminate in an edge, as illustrated in Figs. 4 70 and 5, or the said side walls may be beveled, as indicated in Fig. 6, to form a regular dovetail in the stile A' for the correspondingly-shaped tenon F' of the rail E'.

It will be seen that by the arrangement described the joint between the stile and the rail gives considerable strength to the door, especially as the latter is subjected to a side pressure incident to the opening and closing of the door.

In manufacturing the door the tenon F, copings G, and shoulders H are provided with glue or other binding material previously to driving the tenon into the groove.

Having thus fully described my invention, 85 I claim as new and desire to secure by Letters Patent—

1. A framing-joint having one member formed with a tenon and with copings, the said tenon being reduced at the base, the 90 other member being formed with a longitudinal groove shaped to correspond to said tenon, and provided with clamping-jaws at the outer sides of the groove, the said jaws being adapted to lock over the said tenon and the copings being arranged to engage the said clamping-jaws, substantially as shown and described.

2. A framing-joint having its stile formed with a longitudinal groove, stickings or moldings having clamping-jaws at the outer sides of the groove, the opening between the jaws

being contracted, a rail having a tenon fitting said groove, the said tenon being reduced at the base, and copings to engage said clamping jaws and press the latter against the sides of the tenon at the base thereof, the said copings terminating in shoulders adapted to engage and be seated on corresponding shoul-

ders at the bases of the clamping-jaws, substantially as shown and described.

EDWARD EVERETT SQUIRES.
